UNITED STATES PATENT OFFICE.

DANIEL M. McLAUGHLIN, OF LOUISVILLE, KENTUCKY.

FLUSHOMETER.

1,161,781.

Specification of Letters Patent. Patented Nov. 23, 1915.

Application filed September 17, 1914. Serial No. 862,203.

To all whom it may concern:

Be it known that I, DANIEL M. McLAUGHLIN, a citizen of the United States, residing at Louisville, in the county of Jefferson and 5 State of Kentucky, have invented certain new Improvements in Flushometers; and I do hereby declare the following to be a full, clear, and exact description of the invention, such as will enable others skilled in 10 the art to which it appertains to make and use the same.

My invention relates to flushometers and has for an object to provide a flushing device which will operate in conjunction with 15 service pipes varying in size from the minimum to the maximum in present use.

A further object of the invention is to provide a device having a storage receptacle for air and water to constitute a force 20 for actuating a valve to open a valve chamber and admit a flushing charge to a bowl.

A further object of the invention is to provide a valve chamber containing a valve designed to be operated by a stored up 25 charge of air and water against the pressure of water in a regular service pipe and also the pressure of water in an auxiliary pipe arranged to combine with the water from the service pipe to approximately fill 30 the valve chamber when it is opened, the capacity of which is greater than the combined capacity of the service and storage pipes.

A further object of the invention is to 35 provide a flushometer having an automatic controlling valve between a bowl and a service pipe and designed to be opened and closed by the pressure in the pipe.

A further object of the invention is to 40 provide an automatic valve for regulating a supply of water between a service pipe and a bowl and in conjunction with a storage receptacle containing a charge of air and water for operating the automatic valve and 45 connected with the same by a manually-operative self-closing valve, the storage receptacle and the automatic valve being in direct connection with the service pipe and with an additional storage pipe for increasing 50 the amount of water to be delivered to the bowl.

A further object of the invention is to 55 provide an automatic discharge valve interposed between a bowl and a service pipe and controlled by compressed air and water from a receptacle connected with the valve

and with the service pipe, the compressed air and water in the receptacle being utilized to both open and close the valve leading to the bowl.

A further object of the invention is to provide a flushing device adaptable for use in conjunction with the present standard bowls and having an air and water storage chamber for holding a charge of air and 60 water in direct communication with the service pipe, the inlet to the chamber being controlled by a swinging check valve and the outlet connecting the storage chamber with a flushing valve controlled by a manually operative self-closing valve.

With these and other objects in view the invention consists in certain novel features of construction and arrangement of parts hereinafter fully described and illustrated 75 in the accompanying drawing, it being understood that various changes in the form, proportions and minor details of the device may be made without departing from the spirit of the invention.

In the accompanying drawings Figure 1 is a view in elevation and partly in section. Fig. 2 is a plan view of the same. Fig. 3 is an enlarged detail sectional view of a valve shown in Fig. 1. Fig. 4 is a view in sectional elevation of a slightly modified form 85 of the invention.

Similar numerals of reference are employed to indicate corresponding parts throughout the several figures of the drawings.

Referring to the drawings by numerals, 10 represents a reducing T connected by pipe 11 to a bowl 12. At the end of the reducing T are pipes 13 and 14. Pipe 14 is connected with a five-way fitting adapted to be connected with a water supply pipe. Connected with the five-way fitting are short pipes 16, 17 and 18. The pipe 17 is connected with a reducer 19, provided with a plug 20. Mounted on the reducer 19 is a short pipe 21, which in turn is connected with a T 22, to which are connected pipes 23 and 24. Upon the pipe 24 is secured a reducing L 25, to which is attached an air and water storage chamber 26, which is connected with another reducing L 27. A solid plug 28 has one end secured to the small end of the reducing L 27 and the other end to a coupling 29. The purpose of the solid plug 28 is to close one end of the reducing L 27 and to partly support a self-closing 100 105 110

valve 30. The self-closing valve 30 is provided with a handle 31 for operating the valve. The valve 30 is connected to a pipe 32 by a union 33 and to a pipe 34 by a coupling 35. To the pipe 34 is connected the large end of a reducing L 36, the small end of which is connected to a reducer 37, which is connected to a reducing T 10 by a pipe 13. The pipes 32 and 23 are secured to the T 38 which is provided with a short pipe 39, to which is secured a swinging check valve 40, arranged to open in an upward direction. The swinging check 40 is connected to the five-way fitting 15 by means of short pipes 16 and 41 and a union 42. The five-way fitting 15 is provided with an inlet 43, adapted to be connected with a water supply pipe to furnish water for flushing the bowl 12. A short pipe 18 connects the five-way fitting 15 to an L 44, which in turn is connected with a storage pipe 45, having mounted thereon a swinging check valve 46 arranged to open inwardly but to remain closed when the pipe 45 is charged with air and water. The swinging check valve 46 is provided with a hollow plug 47, closed at the outer end and carrying small perforations 48 through the wall of the plug to admit air to the swinging check and to the pipe 45 when the same has been emptied by flushing the bowl 12. Spaced between the reducing L 36 and the reducer 19 is a valve 49 which consists of a piston head 50, mounted on hollow stems 51 and 52 and two other piston heads 53 and 54 both of which are mounted on a hollow stem 55 with the piston head 54 being connected additionally to a hollow stem 56, closed at the outer end. Upon the outer end 40 of the stem 51 is secured a cap 57 with an opening 58 in the end thereof to receive a sliding member 59. The sliding member 59 is provided with a circular portion 60, somewhat smaller in diameter than the opening 58 and adapted to move longitudinally within the opening. The sliding member 59 is provided at its inner end with a collar 61, larger in diameter than the opening 58 and adapted to secure the member 59 within 50 the cap 57. The sliding member 59 is provided with a shoulder 62, adapted to form a seat upon the end of the cap 57. A spring 63 is interposed between the sliding member 59 and the hollow stem 55 to move the 55 sliding member outwardly within the opening 58 as soon as the valve 49 moves to the right from its normal position. This movement of the valve causes the cap 57 to slide on the circular portion 60 for the purpose 60 of keeping this member free from particles of matter tending to lodge thereon and to clog the opening 58. A sliding action of the member 59 is again accomplished at each flushing of the bowl by the action of 65 the water in the pipes after the bowl has

been flushed, in returning the valve 49 to a normal or closed position and compressing the spring 63, when a pin 64 on the outer end of the sliding member strikes the end of the reducing L 36. The object of the pin 64 is to prevent the end of the reducing L 36 from being closed by the sliding member and to hold the sliding member against outward movement while the valve 49 and the cap 57 connected therewith are returning to their extreme left-hand position. 75

In a modified form of my invention shown in Fig. 4 all of the parts are the same as those shown in the other views with the exception of the air and water storage chamber and the valve chambers, which, instead of being formed of commercial members are each cast in one piece. In the case of the storage chamber 65 in Fig. 4 the reducing L's 25 and 27 are omitted and instead the ends are formed integral with the chamber. In the valve chamber in Fig. 4 an integral member 66 is provided with the small end closed by a plug 67, and the large end by a bushing 68, which also receives the reducing L 36. A seat for the piston-head 53 consists of a ring 69, held in position by a pin 70 passing through the wall of the valve chamber and engaging the ring. In the modified form of the invention the construction other than above noted is identical with the preferred form and the same will be readily understood without further description. 95

In my improved device, including the preferred and modified forms, the operation is as follows: Before water is turned into the flushometer a certain amount of air is held in the pipes leading to the flushometer and in the flushometer itself. When the water is admitted to the pipes it forces air into the storage chamber 26 in Fig. 1 and 65 in Fig. 4, and into the storage pipe 45 which also receives air through the swinging check 46. This air is held under compression by the pressure of the water in the flushometer and the air and water in the storage chamber is held therein by the swinging check to later be used for operating the valve 49. It will be seen that the piston head 53 is 105 larger in diameter than the piston head 54, and it is thus obvious that the water in the five-way fitting and in the pipes connected therewith together with the pressure of the water on the back of the piston head 54 will normally keep the valve in a closed position 115 as shown in Figs. 1 and 4 of the drawings. It will also be seen that the piston head 50 is larger in diameter than the piston head 53, and that upon opening valve 30 and admitting water to the piston head 50 under the pressure of air in the storage chamber 26, the valve 49 will be forced to the right until the piston head 53 moves past the end of the pipe 18 and allows a charge of water 125 130

to enter and flush the bowl. The area of the connections leading from the five-way fitting to the bowl is considerably more than the combined areas of the storage and supply pipes furnishing water to the bowl through the connections. This insures an unobstructed delivery of the water to the bowl and also serves to provide a practically noiseless flushometer by discharging the water from the small into the larger pipe leading from the five-way fitting. As a supply pipe of the regular service size will not furnish enough water at a given moment to supply the large connections leading from the five-way fitting to the bowl, the storage pipe 45 has been provided and connected with the five-way fitting so that at the moment the piston head 53 opens the valve chamber leading to the bowl, the supply of water from the regular service pipe is supplemented by a quantity from the storage pipe sufficient to approximately fill the enlarged connections and to furnish the bowl with the necessary amount for flushing in the time allotted. The water from the storage pipe is discharged by the compressed air held in the end of the pipe, which is sufficient to deliver the supplementary charge of water to the bowl at the moment the piston head 53 opens the valve chamber. The piston head 54 carries substantially equal pressure on each side thereof and therefore the pressure does not interfere with the movement of the valve 49, except when the bowl is being flushed and the pressure in the five-way fitting has been greatly reduced, at which time the pressure on the right of the head 54 is much greater than on the left, and consequently such pressure is utilized to return the valve 49 to its normal or closed position together with a certain amount of pressure on the right of the piston head 53. The piston head 54 also acts as a guide to hold the piston head 53 and stem 55 in alinement with piston head 50 and stem 52. The swinging check valve 40 is so arranged as to open in an upward direction to admit air and water to be forced into the air and water chamber and into the pipes above the valve. With the compressed air and water above the swinging check together with the action of gravity on the valve, the same will normally remain closed to hold the charge of air and water in readiness for actuating the valve 49 when the self-closing valve 30 is manually opened to flush the bowl. At the moment the handle 31 of the valve 30 is raised the valve is opened and a charge of water under the action of the compressed air in the chamber is forced against the outer surface of the piston head 50, moving the valve 49 to the right a sufficient distance to allow water to pass through the five-way fitting from the storage pipe and the regular service pipe to the bowl to flush the same. The valve 30 closes automatically upon releasing the handle 31 and the water held between the valve 30 and the piston head 50, after the bowl has been flushed, serves as a cushion for the return of the valve 49. A certain quantity of this water during the return of the valve 49 is permitted to leak around the circular portion 60 of the sliding member 59 and through the opening 58 in the cap 57 to the hollow stem 51 and 52, into the valve chamber and thence to the bowl. This gradually reduces the pressure on the left side of the piston head 50 and insures the return of the valve 49 to its normal position through the pressure on the right of the piston heads 53 and 54. The piston head 50 is returned to its extreme left-hand position by the stem 55 engaging the spring 63, which engages the sliding member 59 and forces it outwardly in the opening 58 until the pins strike the reducing T 36 and begin to compress the spring. The cap 57 then moves up to the seat 62 of the sliding member and remains in this position until the bowl is flushed again. The telescoping of the stem 55 into the stem 52 serves to align the piston head 50 with the heads 53 and 54 and provides a means for returning the head 50 to its extreme left-hand position and means for forcing the heads 53 and 54 to their extreme right-hand position as the valve is moved in the chamber in either direction by the force of the water in the chamber.

While the device herein described is shown in connection with a bowl it will be obvious that it can equally well be used as a valve for discharging a given amount of water for purposes other than set forth herein.

What I claim is:

1. In a flushometer, a service pipe, a discharge pipe, a fluid receptacle connected with the service pipe, a valve normally under the pressure of the service pipe, a storage pipe connected with the service pipe and with the valve for increasing the flushing charge, means for discharging the contents of the receptacle to actuate the valve for admitting the flushing charge from the storage and service pipes to the discharge pipe, and means for automatically returning the valve to its normal position.
2. In a flushometer, a valve chamber, a normally closed valve positioned in the chamber, a service pipe connected with the chamber, a discharge pipe leading from the chamber, a storage pipe connected with the service pipe and with the chamber, an air and water receptacle connected with the service pipe and with the chamber, a self closing valve interposed between the air and water receptacle and the first mentioned valve whereby, when the self-closing valve is

opened a supply of water under the pressure of the charge of air enters one end of the chamber and opens the valve admitting a supply of water from the storage and serv-
5 ice pipes to the discharge pipe for flushing the same and means to automatically close the first mentioned valve.

3. In a flushometer, a valve chamber, a normally closed valve positioned in the chamber, a service pipe connected with the chamber, a discharge pipe leading from the chamber, an air and water receptacle connected with the service pipe and with the chamber, a check valve interposed between
15 the air and water receptacle and the service pipe and opening in the direction of the flow of water from the service pipe to the air and water receptacle to prevent the return of water to the service pipe when the receptacle is filled, a self-closing valve interposed between the air and water receptacle and the valve chamber whereby, when the last mentioned valve is opened a charge of water under the pressure of the air in the receptacle is admitted to the valve chamber to open the valve and allow a charge of water to enter the discharge pipe from the service pipe and means for closing the first mentioned valve after the closure of the self-
20 closing valve.

4. In a flushometer, a valve chamber having three diameters, three piston-heads, of corresponding diameters disposed therein, the smaller and intermediate heads being
35 mounted on a stem telescoping into a hollow stem carrying the larger head, a discharge pipe leading from the chamber between the larger and intermediate heads, a valve seat in the chamber to receive the intermediate
40 head, a water supply pipe entering the chamber between the intermediate and smaller heads, an air and water receptacle connected with the supply pipe through the valve chamber between the intermediate and smaller heads and extending to the outer
45 face of the smaller head, a pipe connecting the air and water receptacle with the end of the valve chamber containing the larger head, a manually operative self-closing valve
50 interposed between the air and water receptacle and the larger piston-head, a check valve interposed between the air and water receptacle and the supply pipe and opening in the direction of the air and water receptacle whereby, when the self-closing valve is opened a charge of water in the air and water receptacle is prevented from returning to the service pipe and is forced by the air in the receptacle through the self-
55 closing valve into the valve chamber against the larger piston-head, forcing the intermediate piston-head from its seat and admitting a charge of water from the service pipe to the discharge pipe, and means for gradually discharging the water admitted to the

larger piston-head to decrease the pressure thereon.

5. In a flushing device, a valve chamber, a service pipe leading to the chamber, a discharge pipe leading from the chamber, an air and water receptacle connected with the service pipe and with the chamber, a self-closing valve interposed between the air and water receptacle and the chamber, a piston-valve mounted in the chamber and having three piston-heads of varying diameters, the smaller head serving as a guide for the intermediate head and as a medium for actuating the intermediate and larger heads, the intermediate head serving to normally close the valve chamber and the larger head adapted to receive a charge of water from the air and water receptacle upon the opening of the self-closing valve for the purpose of operating the piston valve to admit a charge of water from the service pipe to the discharge pipe for flushing the same, a hollow stem carrying the larger piston-head, terminating in the valve chamber and connected with the discharge pipe and telescoping over a stem carrying the intermediate and smaller piston-heads, a cap mounted on the outer end of the first mentioned stem, an aperture formed in the cap, a sliding member positioned in the aperture and slightly smaller in diameter than the aperture to allow a sufficient quantity of water from the charge actuating the larger piston-head to leak past the head through the stem to the discharge pipe to insure a gradual and positive reduction of the pressure on the head sufficient to reduce below the pressure of the air and water in the receptacle on the outer face of the smaller head to cause the intermediate head to close the valve after the closure of the self-closing valve, and means for moving the sliding member in the aperture to prevent the collection of matter therein and on the sliding member.

6. In a flushing device, a valve chamber, a service pipe leading to the chamber, a discharge pipe leading from the chamber, an air and water receptacle connected with the service pipe and with the chamber, a piston-valve mounted in the chamber consisting of three piston-heads of varying diameters, spaced apart and movably connected together, the intermediate piston-head normally closing the valve chamber under the pressure of the service pipe, means for admitting a charge of water under the pressure of air from the air and water receptacle to the larger piston-head, for moving the intermediate head and opening the valve to admit a flushing charge from the service pipe to the discharge pipe, and means for reducing the charge of water admitted to the larger piston-head after the valve chamber has been opened below the pressure on the smaller head to insure

the closing of the valve after the operation of said means for admitting water to the larger piston head.

7. In a flushometer, a valve chamber, a service pipe leading to the chamber, a discharge pipe leading from the chamber, a fluid receptacle connected with the service pipe through the chamber and with each end of the chamber, a check valve interposed between the chamber and the receptacle and opening in the direction of the flow of water to the receptacle, a valve mounted in the chamber and means for causing the fluid in the receptacle to open and close the valve to deliver water from the service to the discharge pipe.

8. In a flushing device, a valve chamber, a service pipe connected with the chamber, a discharge pipe leading from the chamber, an automatic discharge valve positioned in the chamber and normally remaining closed under the pressure of the service pipe, an air and water storage receptacle connected with the service pipe and with the valve, means for causing the water in the storage receptacle to open the valve to admit a flushing charge to enter the discharge pipe from the service pipe and means for automatically conveying pressure from the storage receptacle to the valve to close the same after the operation of said first-mentioned means.

9. In a flushometer, a service pipe, a discharge pipe, an automatic discharge valve connected with the service pipe and normally remaining closed under the pressure of the service pipe, an air and water storage receptacle connected with the service pipe and with the valve, a container connected with the service pipe and with the valve for holding a flushing charge supplementary to the service pipe, means for causing the water in the storage receptacle

to open the valve to admit a flushing charge to enter the discharge pipe from the service pipe and container simultaneously and means to automatically convey pressure from the storage receptacle to the valve to close the same after operation of said first-mentioned means. 45 50

10. In a flushing device, a valve chamber, a service pipe leading to the chamber, a discharge pipe leading from the chamber, a fluid receptacle connected with the service pipe and with the chamber, a piston-valve positioned in the chamber having three piston-heads spaced apart and connected together, the intermediate piston-head normally closing the valve chamber, means for conveying pressure from the receptacle to one of the end piston-heads to open the valve and means for conveying pressure from the receptacle to the other end piston-head to close the valve. 55 60

11. In a flushometer, a valve chamber, a service pipe leading to the chamber, a discharge pipe leading from the chamber, a fluid receptacle connected with the service pipe through the chamber and with each end of the chamber, a storage pipe connected with the service pipe and with the chamber, a valve mounted in the chamber, means for causing the fluid in the receptacle to open the valve to admit a flushing charge to enter the discharge pipe from the service and storage pipes and means for causing fluid in the receptacle to close the valve after the operation of said first-mentioned means. 65 70 75

In testimony whereof I affix my signature in presence of two witnesses.

DANIEL M. McLAUGHLIN.
